UNITED STATES PATENT OFFICE.

HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

THREAD-CARRIER-OPERATING MECHANISM FOR CIRCULAR-KNITTING MACHINES.

1,152,951.

Specification of Letters Patent.

Patented Sept. 7, 1915.

Application filed September 9, 1914. Serial No. 860,852.

To all whom it may concern:

Be it known that I, HARRY A. HOUSEMAN, a citizen of the United States, residing at Philadelphia, county of Philadelphia, and 5 State of Pennsylvania, have invented a new and useful Improvement in Thread-Carrier-Operating Mechanism for Circular-Knitting Machines, of which the following is a full, clear, and exact description, reference being had to the accompanying drawings, which form a part of this specification.

The object of my invention is to provide means, in that type of circular knitting machine in which the needle cylinder rotates while the cams and the thread carriers are non-rotatable, whereby the thread carriers may be positively moved both into and out of operative relation with the needles.

20 More specifically the object is to provide means to positively move one thread carrier into action and then after a brief interval, to insure the engagement by the needles of the thread carried thereby, positively move 25 out of action the thread carrier previously in action.

The advantage of thus positively operating the thread carriers, as contrasted with the common method of moving them into action by springs and out of action against the tension of their springs, is obvious.

In a patent issued to me January 9, 1900, No. 640,769, I have disclosed means for positively moving thread carriers both into and 35 out of action, but such means were applied to a machine in which the needle cylinder was stationary while the cams and the thread carriers rotated. The present invention utilizes certain features set forth in 40 said patent, but supplements them by special features of an inventive character adapted to insure the successful positive operation of the thread carriers in both directions in a machine in which the needle cylinder 45 is the rotatable element.

In the drawings, which show a preferred embodiment of my invention, Figure 1 is a sectional side elevation of a portion of a knitting machine embodying my invention. 50 Fig 2 is a plan view of the same and Fig. 3 is a sectional view taken on the line 3—3 of Fig. 1.

A table *b*, mounted on the machine frame

a, carries a needle cylinder *c*, which has fastened to it the gear *d*, driven by means not shown but well known in the art. The thread carriers *e*, *e'*, *e²* and *e³* are shown as pivotally mounted on a pin *f*. Four thread carriers are shown, but the number may vary according to the requirements of the work. The tails of the thread carriers are actuated by cams *g*, *g* and *g'*, on the upright lever *h*, which, between its ends, carries a shaft *j*, which is rockable, and also 60 slideable in the direction of its axis, in bearings *k*, *k*, on the machine frame. 65

The cam *g'* is of a width, preferably, about the same as the thickness of a thread carrier, while the cams *g*, *g*, are each of a width sufficient to engage and actuate three 70 of the thread carriers. The cam face of the cam *g'* is inclined upward, so that any inactive thread carrier that it engages will be moved into operative position. The cam face of each of the cams *g* is inclined downward, so that any active thread carrier that it engages will be moved into inoperative position. The cam *g'* is located in advance of the cams *g* to insure the rendering active of one carrier before the other carrier is rendered inactive. Further, in the forward 75 movement of the lever *h*, there is a slight dwell, as will be hereinafter more fully explained, after cam *g'* has acted and before cam *g* acts, to insure the placing of the new thread in the needles before the old thread is removed therefrom. 80

It will be understood that by sliding the shaft *j* in its bearings, the cam *g'* may be caused to align with any desired thread carrier, while the remaining thread carriers will be aligned with one or both of the cams *g*. Then, by rocking the shaft *j*, the first named thread carrier will be rendered operative by the cam *g'*, while any of the 95 other thread carriers that is in active position will be rendered inoperative by one of the cams *g*.

A spring *l* normally holds the lever *h* in its retracted position, while a spring *p*, 100 coiled about the shaft *j*, and confined between the lever *h* and one of the bearings *k*, tends to slide the lever *h* and its shaft *j* laterally in one direction. Positive means, automatically actuated, are provided to position the shaft laterally and then to swing 105

the lever h forwardly and these means will now be described.

5 A pattern chain shaft m has a ratchet wheel n , which is given an intermittent motion by means not shown but well known and commonly employed on all circular knitting machines. The shaft m carries a pattern chain o and a cam wheel s .

10 The pattern chain o is provided with lugs o' of different height, which lugs actuate one arm of a bell-crank lever r pivoted on the machine, the other arm of the bell-crank engaging an end of the shaft j . Whenever a lug o' engages the bell-crank r the shaft j 15 and lever h will be moved laterally so as to position the cam g' to act upon one of the thread carriers. The extent to which the lever h will be laterally shifted and the thread carrier which will be alined with the 20 cam g' depend, obviously, on the height of the lug carried by the pattern chain.

25 The cam wheel s carries a number of cams s' , all of the same contour, and adapted to actuate a pin t carried by the tail of lever h , and thereby swing the lever h forward as before described. Pin t is long enough to be in the path of the cams s' in the different lateral positions to which lever h is shifted.

30 The cams s' are spaced apart the same angular distance as the lugs o' . There may be said, therefore, to be a cam s' for each lug o' and a corresponding lug and cam are so relatively positioned that the cam face of the lug o' will operate in advance of the 35 cam face of the corresponding cam s' , thereby effecting a lateral shift of the lever h prior to its advance swinging movement.

35 As before described, it is desirable to provide, in the advance movement of the lever h , a dwell between the operation of cam g' and the operation of cam g . This is effected by shaping the face of each cam s' so as to provide an upwardly inclined face followed successively by a flat face and 40 another upwardly inclined face. Thus, after the lever h is shifted laterally, it is swung forward to cause cam g' to operate the carrier in line therewith, then it is held stationary to give time for the thread to be 45 caught and knitted a certain distance into the fabric, and then its forward motion is completed to allow one of the cams g to move the previously operative carrier out 50 of action. During the time that a cam s' 55 is thus actuating lever h , the high face of the corresponding lug o' is holding bell-crank r and shaft j stationary. The lug o' rides from under bell-crank r just after the corresponding cam s' rides beyond pin t . 60 Consequently lever h is first retracted by the spring l and is then moved laterally by the spring p until it is acted upon by another lug on the pattern chain.

65 It will be understood that when a thread carrier is moved into inactive position, there-

by raising the thread carried out of range of the revolving line of needles, the thread will be severed by any well known means.

The thread carriers turn on their pin f with sufficient friction to insure their remaining in whatever position they are placed by the cams g, g' .

Having now fully described my invention, what I claim and desire to protect by Letters Patent is:

75 1. In a circular knitting machine, the combination with a rotatable needle cylinder, of a series of non-rotatable independent thread carriers, positively operated mechanism adapted to positively move one carrier into action and another carrier out of action, and pattern-controlled mechanism to establish operative relation between said mechanism and different combinations of carriers to cause said mechanism to so operate to 80 effect any predetermined change of yarn.

85 2. In a circular knitting machine, the combination with a rotatable needle cylinder, of a series of non-rotatable independent thread carriers, positively operated mechanism adapted to positively move one carrier into action and another carrier out of action, and pattern-controlled mechanism adapted to first select the carriers to be 90 moved respectively into and out of action and then positively operate the same to effect the change of yarn.

95 3. In a circular knitting machine, the combination with a rotatable needle cylinder, of a series of non-rotatable independent 100 thread carriers, positively operated mechanism adapted to positively move said thread carriers into and out of action, and pattern means to establish operative relations between said mechanism and different combinations of carriers.

105 4. In a circular knitting machine, the combination with a rotatable needle cylinder, of a series of non-rotatable independent 110 thread carriers, positively operated mechanism adapted to positively move said thread carriers into and out of action, pattern means adapted to establish operative relations between said mechanism and different pairs of carriers to dictate the movement of 115 one carrier into, and the other out of, action, and positively operating means to positively actuate said mechanism to effect the change of yarn.

120 5. In a circular knitting machine, the combination with a rotatable needle cylinder, of a series of non-rotatable independent thread carriers, mechanism adapted to positively move said thread carriers both into and out of action, pattern-controlled means 125 adapted to preliminarily position said mechanism to dictate a change of carriers, and pattern-controlled means to positively actuate said mechanism.

125 6. In a circular knitting machine, the

combination with a rotatable needle cylinder, of a series of non-rotatable independent thread carriers, positively operated mechanism adapted to positively move one carrier into action and another carrier out of action, a set of pattern cams adapted to actuate said mechanism to bring it into operative relation with different pairs of carriers, and pattern cam mechanism adapted to actuate said mechanism to effect a change of yarn.

7. In a circular knitting machine, the combination with a rotatable needle cylinder, of a plurality of non-rotatable independent thread carriers, cams adapted to respectively move one carrier into action and another carrier out of action, and means to shift said cams to preliminarily bring them into operative relation with different combinations of carriers.

8. In a circular knitting machine, the combination with a rotatable needle cylinder, of a plurality of non-rotatable independent thread carriers, cams adapted to respectively move one carrier into action and another carrier out of action, means to shift said cams to preliminarily bring them into operative relation with different combinations of thread carriers, and means to actuate said cams to cause the first cam to complete the movement into action of one carrier before the other cam withdraws from action the other carrier.

9. In a circular knitting machine, the combination with a rotatable needle cylinder, of a plurality of non-rotatable independent thread carriers, positively operated mechanism comprising a part adapted to shift a thread carrier into action and a part adapted to shift a thread carrier out of action, and pattern mechanism adapted to establish operative relations between each of said parts and different carriers.

10. In a circular knitting machine, the combination with a rotatable needle cylinder, of a plurality of non-rotatable independent thread carriers, cams adapted to respectively move one carrier into action and another carrier out of action, pattern mechanism, and means controlled thereby to preliminarily bring said cams into operative relation with different combinations of

thread carriers and to then successively operate said cams.

11. In a circular knitting machine, the combination with a rotatable needle cylinder, of a plurality of non-rotatable independent thread carriers, cams adapted to respectively move one carrier into action and another carrier out of action, pattern mechanism, means actuated by the pattern mechanism to preliminarily shift said cams into position to bring them into operative relation with different combinations of thread carriers, and means actuated by the pattern mechanism to thereafter cause said cams to operate successively.

12. In a circular knitting machine, the combination with a rotatable needle cylinder, of a plurality of non-rotatable independent thread carriers, a cam for moving inactive carriers into action adapted to be alined with one of said carriers, cams for moving active carriers out of action arranged on opposite sides of the first cam, means to shift said cams in unison to cause the first cam to aline with any one of said carriers, and means to advance said cams in unison into operative relation with the carriers.

13. In a circular knitting machine, the combination with a rotatable needle cylinder, of a plurality of non-rotatable independent substantially radially extending thread carriers, a central cam for moving inactive carriers into action adapted to be alined radially with one of said carriers, cams for moving active carriers out of action arranged on opposite sides of and beyond the first cam, means to shift said cams laterally in unison to cause the first cam to aline radially with any one of said carriers, and means to impart to said cams two successive movements in an inward radial direction, thereby causing the central cam to first move one carrier into action and one of the side cams to then move out of action a carrier previously in action.

In testimony of which invention, I have hereunto set my hand, at Philadelphia, on this 5th day of September, 1914.
